CLAIM

The ornamental design for a toiletry package, as shown and described.

DESCRIPTION

FIG. 1 is front perspective view of a toiletry package showing my new design;

FIG. 2 is a front elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken line showing of toiletry articles in FIG. 1 is for illustrative purposes only and forms no part of the claimed design.
